UNITED STATES PATENT OFFICE.

MONROE INGERSOLL, OF INDIANAPOLIS, INDIANA, ASSIGNOR OF ONE-HALF
TO FRANCIS ROBININS, OF SAME PLACE.

COMBINED SWING AND CHAIR.

SPECIFICATION forming part of Letters Patent No. 289,267, dated November 27, 1883.

Application filed October 25, 1883. (No model.)

To all whom it may concern:

Be it known that I, MONROE INGERSOLL, a citizen of the United States, residing at Indianapolis, in the county of Marion and State 5 of Indiana, have invented a new and useful Combined Swing and Chair, of which the following is a specification.

My invention relates to an improved combined swing and chair, my object being to 10 provide a swinging chair in which a child may swing sitting upright or reclining, and to combine also with a swing-chair folding legs, which may support the chair independently of its swinging support, all as hereinafter 15 fully described.

The accompanying drawings illustrate my invention.

Figure 1 is a perspective view of my chair as a swing in a sitting position. Fig. 2 is a 20 side elevation, showing the chair as a swing in a reclining position. Fig. 3 is a perspective showing the chair detached from its swinging support and resting on its folding legs.

25 *a* is the seat; *b*, the back, which is pivoted to the seat near its back edge on each side at *c*. Near the front edge of the seat on each side are pivoted at *d* uprights *e e*, which extend below the seat to form supports for the 30 foot-rest *f*, which is rigidly secured thereto. Said uprights extend also above the seat, and form supports for the side pieces, *g g*, which are pivoted to said uprights; and also to the back at *h*. A ratchet-bar, *i*, is pivoted to 35 the back at *h*, and engages a pin, *k*, projecting from the edge of the seat, for the purpose of holding the back in an upright position. At each of the four corners of the seat is secured an upright rod, *l*, terminating in an 40 eye. On said rods are slipped short uprights *m m* and cross-bars *n n*, thereby forming firm side guards when the chair is extended, as in Fig. 2. Hinged to the under side of the seat are four legs, *q q* and *r r*. Said legs are each 45 formed of two pieces of nearly equal length, hinged together end to end, so as to fold one upon the other. Legs *q q* are permanently connected by a cross-bar, *s*, and are hinged to the under side of the seat near the front edge. 50 Said cross-bar passes through said legs and projects outside far enough to receive the legs *r r*, which are each provided with a hole at *x*,

through which cross-bar *s* projects when the legs are extended, and are hinged to the seat outside of legs *q q*. Legs *q q* and *r r* are adapted to fold each upon itself, and up against the under side of the seat, where they are held by hooks *t t*. 55

The chair is suspended from the ceiling or other suitable support by means of double 60 cords *u* and *v*, the lower ends of which are secured by hooks or otherwise to the eyes *l*. A third pair of guard-cords, *w w*, are also secured to the ceiling or other support, and attached to the upper end of back *b*—one on 65 each side—for the purpose of preventing the back from falling too far when extended, as shown in Fig. 2.

As thus constructed, a comfortable swing is formed when the device is in the position 70 shown in Fig. 1, which may be changed to a swinging couch, without removing the occupant, by releasing the ratchet-bar *i* and allowing the back to fall, which at the same time raises the foot-rest *f*, as shown in Fig. 2. 75

When it is desired to form a self-supporting chair, hooks *t t* are released, and the legs, unfolding, assume the position shown in Fig. 3, legs *r r* being sprung outward far enough to slip over the projecting ends of cross-bar *s*. 80

It will be observed that the two pieces forming each leg are hinged together in such a manner that they are kept from folding together by the weight of the chair, which is detached from the suspending-cords. 85

I claim as my invention—

1. The combination, with a folding reclining-chair, of the suspending-cords *u* and *v* and guard-cords *w w*, substantially as and for the purpose specified. 90

2. The combination, with a folding reclining-chair, of rods *l*, uprights *m*, and cross-bars *n*, substantially as and for the purpose specified.

3. The combination, with a chair adapted 95 to be suspended by cords, of the folding legs *q q* and *r r*, hinged to said chair, and cross-bar *s*, all combined substantially as and for the purpose specified.

MONROE INGERSOLL.
